2 Claims. (Cl. 235—58)

Our invention relates to a record card-controlled business machine and, more particularly, to a total punching equipment for card-controlled tabulating machines.

5 An object of our invention is the provision of a tabulating machine adapted to analyze cards sorted in groups and to automatically register the total of each group by printing and perforating operations. Further objects are to provide 10 automatic card feeding means feeding pre-sorted punched cards to be analyzed through the tabulator and feeding blank cards through the total punching mechanism of the tabulator in the succession of the groups of punched cards; to provide 15 a total punching attachment adapted to be applied to existing tabulating machines without the necessity of materially modifying the construction thereof, to provide amount-storing means adapted to be set by the total-representing 20 elements of a tabulating machine and to control a card punch; to provide a card punching device having a full complement of punches with a multiple translator which is adapted to be set under control of the tabulating machine to cause one 25 or more totals computed in certain tabulator units to be recorded in any desired card field by perforation of blank cards fed to the punching device under control by the totalling mechanism of the tabulator.

30 Further objects of our invention will appear from the description of a preferred embodiment of our invention following hereinafter and the features of novelty will be pointed out in the claims.

35 In the drawings the invention is illustrated as applied to the Powers tabulator which is disclosed in numerous patents, for instance in Patents No. 1,245,502, No. 1,376,555 and No. 1,388,271. It is to be understood, however, that our invention is also applicable to other types of tabulating machines. In the drawings

40 Fig. 1 is a partial vertical section through a Powers tabulator and the amount-storing means forming part of our improved total punching equipment, the section being taken along line A—B of Fig. 2.

Fig. 2 is an elevation of the upper part of Fig. 1 viewed from the left.

45 Figs. 3, 4 and 5 are similar to Fig. 1, but illustrate the elements in successive positions during a totalling cycle,

Fig. 6 illustrates a denominational storing element adapted to convert a digit into its complement,

50 Fig. 7 is a vertical section extending fore-and-

aft through the total punching attachment including the storing means, the selector slides cooperating therewith, the multiple translator, the punching means and the total card feeding mechanism,

5 Fig. 8 is a side view of the multiple translator.

In the drawings we have illustrated so much only of the Powers tabulator as is necessary for an understanding of the invention.

First, an explanation of the principal elements 10 of the Powers tabulator will be given to facilitate the understanding of the improved punching attachment cooperating therewith.

15 Each of the type sectors 2 of the tabulator is pivotally carried by a shaft 1 mounted in the frame of the machine and carries the numeral types 4 adapted to be imprinted on a record sheet placed on the paper platen 3. The sector 2 is provided with a rearward extension 5 forming a hook to which a spring 7 is attached. The other end 20 of spring 7 is anchored to a toothed actuating sector 8 and tends to relatively displace the sectors 2 and 8 so as to keep a pin 9 projecting from the sector 8 against the end wall of a slot 10 provided in the sector 2. The teeth 11 of the actuating sector 8 cooperate with a totalizer wheel 12 in the conventional manner. The actuator wheel has a ten-carrying tooth 13 which cooperates with a lug 14 of a ten-carrying lever. During totalling cycles the lug 14 constitutes a stop which 25 limits the resetting turn of the totalizer wheel 12 and thus determines the position of the sectors 2 and 8 in accordance with the digit which was represented by the totalizer wheel. The actuating sector 8 has a heel 15 adapted during accumulating cycles to cooperate with one of a number of sector stops 16 which is selected and lifted by the sensing mechanism. One only of the sector stops 16 is shown in the drawings.

30 35 In a type sector 2, an actuating sector 8, a totalizer wheel 12 and a ten-carrying lever having lug 14 constitute a denominational unit of the computing mechanism of the Powers tabulator. The entire computing mechanism may comprise 40 45 50 55 60 65 70 75 80 85 90 95 100 105 110 115 120 125 130 135 140 145 150 155 160 165 170 175 180 185 190 195 200 205 210 215 220 225 230 235 240 245 tached to shaft 17. A link 21 is pivoted on a stud 20 projecting from sector 19 and extends upwardly and rearwardly to a lever 24 and is linked to the latter by a pivot 22. The lever 24 is pivoted on a horizontal shaft 23 and its lower end is provided with a curved cam slot 25 embracing a roller 26 mounted on one of a pair of levers 27. The levers 27 are pivotally mounted on shaft 1 and carry a universal restoring bar 28 extending in front of the vertical arms of sectors 2 of the tabulating unit under consideration.

During any cycle of operation the sector 19 oscillates and imparts a forward and upward to-and-fro movement to the restoring bar 28 thereby permitting the sectors to advance in the direction of the arrow and then positively restoring the sectors to initial position. Each sector 2 tends to follow the universal bar 28 on its forward stroke owing to the action of a spring 29 exerting a downward pull on the end of arm 6 attached to the projections 5. The springs 29 are anchored at suitable points of the machine frame. The forward movement of the sector is limited during tabulating cycles by a card-controlled stop 16 and during totalling cycles owing to the stoppage of the totalizer wheel in its zero position.

The shaft indicated at 35 is a continuously rotating main shaft in the tabulator head from which the rocking motion of shaft 17 is derived. It is believed that the foregoing description of the principal elements of the Powers tabulator will suffice for the purpose of describing our invention. For a more detailed disclosure, particularly of the means for feeding the punched cards to and from the sensing mechanism controlling the sector stops 16, reference may be had to the patents above referred to.

For the purpose of transferring items or totals set up in the tabulating units to a recording device, particularly a card punch, we have provided the attachment described hereinafter.

We have attached a gear 36 to shaft 35 and have added the mechanism illustrated in Fig. 1 above shaft 35. This mechanism comprises a shaft 37 mounted in the machine frame on which a gear 38 is freely rotatably arranged to mesh with gear 36 and to be permanently driven thereby in the direction of the arrow in Fig. 1. A suitable one-revolution-clutch of any desired type, such as that shown in Patent No. 1,810,317, issued to W. W. Lasker on June 16, 1931, and which need not be illustrated in detail, is so arranged as to connect gear 38 to an eccentric 39 attached to shaft 37. The one-revolution-clutch including a disc 40 will be engaged by withdrawal of a latch 43 from a lug 50 of disc 40. The latch 43 is mounted on a stud 42 projecting from the lower end of a two-armed lever 41 depending from a stud 45 fixed to a bracket 46 which is mounted on a transverse bar 47 of the machine frame 18. The latch 43 is guided in a grooved block 44 suitably supported by a spring. A spring 48 attached to the bracket 46 and to lever 41 tends to keep lever 41 against an abutment 49 and to draw latch 43 into engagement with lug 50, whereby the one-revolution-clutch is normally kept in disengaged condition in which the eccentric 39 is at rest. Lever 41 may be operated from various elements of the tabulator depending on the nature of the amount to be registered by the card punch. If totals are to be registered, lever 41 is operated from one or the other or both total shafts of the tabulator. The total shaft of a Powers tabulator is shown in Fig. 1 of U. S. Patent No. 1,926,203, issued to W. W. Lasker on September

12, 1933. This shaft is designated by the numeral 30. An arm on this total shaft is connected by a linkage to the end of lever 41 so that operation of the total shaft releases clutch disc 40. It is believed that the means connecting lever 41 with the total shaft or total shafts need not be described in detail, as it will be understood that any time the total shaft is rocked to initiate the totalling operation, the upper end of lever 41 will be rocked in the direction of the arrow shown in Fig. 1, thereby tripping the one-revolution-clutch 40 and imparting a single revolution to the eccentric 39.

The strap of the eccentric 39 is integral with the connecting rod 51 which is linked to the arm 52 of a shaft 54. The shaft 54 extends transversely across the top of the tabulator and is mounted in brackets 55 suitably attached to the frame 18.

Shaft 54 carries as many pairs of arms 56 as 20 tabulating units are provided, each pair of arms 56 being coordinated to one tabulating unit. The arms 56 of each pair which are splined to shaft 54 are connected by parallel rods 57 and 61 to constitute a rigid rocking frame which is rocked 25 by the eccentric 39 once at any totalling cycle. Between the two cheek plates 56 of each rocking frame, there are loosely mounted on shaft 54 as many storing sectors 58 as corresponds to the denominational capacity of the coordinated tabulating unit. Each storing sector may assume any one of ten differential positions relative to the rocking frame 56, 57 and 61 and may be arrested in this position by a pawl 60 pivotally mounted on rod 61 and cooperating with ratchet teeth 59 35 provided on the upper face of the sector. A separate pawl 60 is provided for each sector 58 and is connected with an extension 66 of the same by a spring 67 which tends to keep pawl 60 in engagement with the ratchet teeth 59 and to turn sector 58 in clockwise direction relative to the rocking frame. Rod 57 forms a stop limiting such clockwise movement. In the path of the upwardly projecting arms of pawls 60 there is interposed a transverse stop bar 62 carried by suitable extensions of frame 18. When the rocking frame 56, 57 and 61 assumes its left, or rearward, end position as shown in Fig. 5, all of the pawls 60 are held disengaged thereby permitting the storing sectors 58, 66 to swing to engagement with the rod 57. Each storing element includes the stepped extension plate 66 detachably secured to the sector 56 and a depending sensing pin 64 pivoted to a forwardly projecting arm of the sector. The lower ends of the sensing pins 64 65 are guided for vertical movement within a suitable comb 65 extending between brackets 55 and are positioned directly above the rearward extensions 6 of the type sectors 2. The rearward lower face of the plate 66 is formed with ten 60 steps which correspond to the digits to be transferred to the punching or other recording device and cooperate with a punch setting slide 107 which will be described later.

From the foregoing description it will be apparent that a type sector 2, a sensing pin 64, a storing sector 58, a locking pawl 60, a stepped plate 66 and a punch selecting bar 68 are provided in each denominational plane of the tabulator.

The operation of the tabulator and the storing device is as follows: Fig. 1 illustrates the elements in the position they assume just after the beginning of a totalling cycle. The totalizer wheel 12 is in engagement with the teeth 11 of 75

the actuating sector 8 which has just started its forward movement and has advanced the type sector 2 one pitch, whereby the zero type has been moved to printing position opposite to the platen 3. At this instant lever 41 is operated from the total shaft thereby withdrawing latch 43 from the lug 50 of disc 40 and thus engaging the one-revolution-clutch which connects the eccentric 39 with the continuously revolving gear 38. 5 When the one-revolution-clutch is in its normal disengaged condition, it arrests the eccentric 39 shortly before the lower dead center position of the same, as will appear from Fig. 1. Therefore, the arm 52 is slightly lowered upon engagement 10 of the one-revolution-clutch and rocks the frames 56, 57 and 61 through a small angle in anti-clockwise direction. This rocking motion forces the pawls 60 against the stop bar 62 whereby the pawls 60 are disengaged from the ratchet teeth 59 and permit the sectors 58 to move into the position illustrated in Fig. 5 in which they abut against rod 57. In this manner the storing sectors are cleared of the amounts set up in the preceding totalling cycle. 15

20 Further rotation of shaft 35 causes sector 19 to continue its turn in clockwise direction until it arrives in its forward end position illustrated in Fig. 3. At the same time link 21 has moved arms 21 to their forward end position in which 25 the universal restoring bar 28 has fully released the sectors. All of the type sectors 2 and the actuating sectors 8 connected to the same by springs 7 have so far advanced under action of springs 29 as to turn the meshing totalizer 30 wheels 12 to zero position in which the ten-carrying teeth 13 engage the lugs 14 of the ten-carrying pawls. In this manner the type sectors 2 are differentially set to permit the total line including totals of accumulated items in some 35 tabulating units and designating numbers in other tabulating units, as described for instance in the patent to Lasker No. 1,388,271.

The matter printed in the total line including totals and designating numbers is now set up in the storing elements and preserved for later transfer to the total punching device. After the storing elements have been cleared at the beginning of the totalling cycle, the continued revolution of eccentric 39 imparts a clockwise turn to the rocking frame 54, 56, 61 and the sectors 58 tend to follow this turn under action of springs 67 until they are arrested by engagement of the sensing pins 64 with the extensions 6 of the type sectors 2. After the sectors 58 have been thus arrested 50 in differential positions, each rocking frame continues its clockwise turn stretching springs 67 and carrying pawls 60 with it which ride over the teeth 59 of the arrested sectors 58, as illustrated in Fig. 3. After the eccentric has passed through 55 its upper dead center position, the rocking frame returns in anti-clockwise direction carrying the sectors 58, which are kept by the pawls 60 in differentially set positions as shown in Fig. 4 with it.

Considering one of the storing sectors 58 it will be appreciated that shortly after the beginning of the totalling cycle it bears against rod 57 under action of spring 67, while the pawl 60 engages the teeth 59. Assuming that the coordinated type sector 2 be set to print the digit "5", the storing sector 58 will be arrested by engagement of its sensing pin 64 with the extension 6 after the rocking frame has performed half of its stroke. The rocking frame, however, continues its turn and carries pawl 60 along until pawl 60 has engaged 65 the fifth tooth 59, as shown in Fig. 3. The angle

embraced by the teeth 59 and the angle of movement of the rocking frame correspond to the path described by extension 6.

Therefore, the pawl 60 will be brought to engagement with that tooth 59 which corresponds to the type 4 of the associated sector 2 which is in printing position. During the continued revolution of shaft 35 the sector 19 and the arms 21 connected therewith are turned back and at the same time the rocking frames 56 are restored to 10 initial position. During this movement the restoring bar 28 restores the type sectors 2 of the tabulating machine and the rocking frames 56 turn the storing sectors 58 and the stepped plate 66 connected thereto to the position shown in Fig. 15 4. When the type sectors have been restored, the stepped plates 66 arrive in position to cooperate with the sector slides 68. After their arrival in this position, the one-revolution-clutch is automatically disengaged and the step of each plate 20 66 which corresponds to the digit set up by the associated type carrier remains in the horizontal path of movement of the associated selector slide 107, whereas the type carrier itself is restored. The storing elements will not be cleared until the 25 next subsequent totalling cycle commences. Hence, the resumption of tabulating operation after the total printing cycle need not be delayed on account of the total punching operation.

The ratio of transmission of the gears 36 and 30 38 is so chosen that the gear 38 imparts such a speed to the eccentric 39 as to withdraw the sensing pins 64 faster than the type sectors 2 are restored. In this manner time is saved for setting the punching or other registering device and the 35 proper adjustment of the storing means relative to the type sectors is facilitated.

It will be appreciated that the one-revolution-clutch may be tripped at other times than during totalling cycles, for instance during some tabulating cycles, if it is desired to transfer items set up in the tabulator under card control to the 40 registering device.

If it is desired to record the complement of a number set up in a tabulating unit, we substitute 45 complementary stepped plates 66' as shown in Fig. 6 for those normally employed. The plate 66' differs from plate 66 in that it presents its outermost 0-step, instead of the innermost 9-step to the punch selecting slide 107 when assuming 50 its normal position within its rocking frame. The complementary plate 66' used in the unit's denominations may be so profiled as to transmit a true ten-complement as will be readily understood by anyone skilled in the art. 55

While the shaft 54 carrying the storing means and the shaft 37 carrying the driving eccentrics therefor are mounted within suitable extensions of the frame of the tabulator, the punching mechanism including the punch selectors, the multiple 60 translator, the punches and the card feeding means is mounted in a separate frame which is preferably guided by suitable rollers on rails attached to the same base plate on which the tabulating machine rests. The rollers running on the 65 rails of the base plate are preferably carried by eccentrics which may be turned by the operator so as to suitably adjust the punching mechanism to proper position relative to the tabulating machine.

The upper part of the frame comprises two 70 castings 101 which are suitably connected by a number of transverse bars or rods which support and guide the various elements to be described hereinafter. Within this frame the horizontal selector slides 107 are suitably guided to be lon- 75

itudinally shiftable, one such slide being provided for each stepped sector 66 and being positioned within the vertical plane of said sector.

For transferring the amounts set up in the storing elements to the punching mechanism, each selector slide 107 is caused to move to the left with reference to Fig. 7 until it engages the opposed step of the coordinated plate 66. To this end, a universal bar 104 extending transversely of and below the selector slides 107 is guided to be movable parallel to itself. The ends of the universal bar 104 are guided between horizontal rails 144 attached by screws to the castings 101. The universal bar 104 is reciprocated by suitable means to be described later. A comb 140 attached to bar 104 forms hooks 138 wherefrom springs 137 are stretched to the rearward ends of the slides 107, each spring tending to pull its associated slide towards the left with reference to Fig. 7, when the universal bar 104 releases the slides by movement toward the left. During such movement the selector slides 107 will be arrested in differential positions by the stepped plates 66, as will be readily understood.

The universal bar 104 is reciprocated by three arms 143 which are splined to a common shaft 145. One of these arms is formed by a bell-crank carrying a cam roller which engages a cam groove provided in a cam 149. The cam 149 is attached to a shaft 146 which is mounted in the frame 101 and is driven through the intermediary of a pair of bevel gears by a substantially vertical shaft 151 which, in its turn, is cooperatively connected to the main drive shaft 181' by another pair of bevel gears 153, 154. The cam 149 is so designed that a revolution of shaft 181' will cause the universal bar 104 to move quickly towards the left and to pause in its left end position for about half the period of revolution of shaft 181' and then to quickly return to its initial position.

Each selector slide 107 carries a heel 113 which normally rests against the universal bar 140 under action of spring 137, and carries also a head 112 in which an interponent 111 is guided for vertical movement. The reduced lower end of this interponent terminates just above the multiple translator which is interchangeably inserted between the castings 101. The upper end of the interponent carries a roller 109 which is kept in contact with the lower face of a vertically reciprocating plate 103 by a rail which is attached to plate 103 in spaced relation and supports roller 109 from below. The plate 103 extends horizontally and transversely across the selector slides 107 and its ends are formed integral with sleeves guided on vertical rods 127. The rods 127 are mounted in suitable bosses of the castings 101. During the interval in which the universal bar 104 remains in its left end position after the selector slides 107 have been differentially set, the plate 103 is lowered and lifted. In its downward movement it depresses the interponents 111 which, in their turn, depress the selected connecting wires which are guided in the multiple translator for vertical displacement.

The following means are provided for moving plate 103 up and down. A shaft 128 is journaled in brackets attached to plate 103 and carries pinions 129 meshing with rack teeth cut in the rods 127. Hence, a turn of shaft 128 will displace plate 103 parallel to itself. The shaft 128 has an arm which is connected by a link 132 with one arm of a bell-crank 133 pivotally mounted on a stud projecting from the castings 101. The other arm of bell-crank 133 carries a cam roller

134 engaging a suitable groove of a cam disc 136 which is splined to shaft 146.

The multiple translator is of substantially the same construction as that ordinarily employed in the Powers tabulator and comprises a box-shaped frame in which connecting wires are guided for vertical displacement. These wires may extend from the plane of movement of any slide 107 to any denominational row of punch setting pins 190. The multiple translator has been but slightly modified for the purpose of our invention. Plates 182 are attached to the end walls of the translator box near the top thereof and are provided with two projecting upper studs 183 and two lower studs 184 as shown in Fig. 8. Horizontal guiding rails 181 are attached to the inner faces of the castings 101. These guiding rails serve to facilitate the insertion of the multiple translator in that the latter is guided by its studs 183, 184 thereon when moved to its operative position until the studs 183 engage suitable recesses provided in the upper face of the guiding rails 181. Moreover, the bottom plate of the translator box is provided with a hole 185 adapted to be engaged by a stud 179 projecting upwardly from the frame 186 of the basket containing the punch setting pins 190, when the translator box, pushed forward along the rails 181, arrives in its proper position. In this manner, the accurate position of the multiple translator relative to the other elements of the device is secured without interference with the easy removal or replacement of the multiple translator.

The punching means positioned below and adapted to be set up by the multiple translator are identical in construction and operation with those employed in the perforating machine which is in common use and known on the market as the Powers key punch disclosed for instance in U. S. Patents No. 1,307,682, No. 1,684,546 and No. 1,311,566. Therefore, a detailed description of the punching device proper and the associated card feeding means is deemed unnecessary. It may be mentioned, however, that whenever shaft 181' performs one revolution, a reciprocatory card picker 187 feeds the lowest card from the stack of blank cards in the magazine 188 in between two pairs of feed rollers 189 which introduce the card into a card pocket formed by two perforated plates attached to the frame 192. Subsequently, the frame is lifted to press the card against punches 191, one punch being provided for each index point in the card, and those punches, which are kept depressed by set selecting pins 190, punch holes in the card while the other punches are lifted by the card. The selecting pins 190 which have been depressed by connecting wires of the multiple translator may be temporarily locked by suitable means, as is well known in the art and as is shown in Fig. 3 of Patent No. 1,305,557, issued to James Powers on June 3, 1919. Then the frame 192 is lowered and the punched total card is ejected by a pair of rollers 193 and deposited in a magazine 194. Frame 192 is lifted and lowered by an eccentric which is suitably operated from shaft 181'.

Shaft 181' is operated from a suitable continuously rotating shaft, preferably driven by an electric motor not shown in Fig. 7, through the medium of a one-revolution-clutch of the type shown in Patent No. 1,810,317 which is controlled from the total shaft of the tabulator. For this purpose, the total shaft is suitably connected to a slide 157 so as to move the latter towards the right during a totalling cycle. The

slide 157 is guided in an extension of the tabulator frame. Brackets 175 attached to the castings 101 carry a lever 173. The lower end of this lever bears against slide 157 when the total 5 punching attachment has been properly positioned relative to the tabulator, while the upper portion is connected by link 176 to a bell-crank 178 which operates a link 180. A link 180 extends from the horizontal arm of the bell crank 178 to the horizontal arm of another bell crank 177 (which appears in elevation in Fig. 7). The vertical arm of bell crank 177 is in turn pivotally connected to the tripping lever 195 of the one revolution-clutch which couples the power source 10 to shaft 181'. Since the clutch is well known and not claimed as our invention the disc and all other parts aside from the tripping lever have been omitted in the drawings. Thus, it 15 will be seen that whenever the total shaft is turned to initiate a totalling cycle, the slide 157 will be shifted towards the right and will cause the one-revolution-clutch to be tripped, whereby the above described card feeding and punching operation will be initiated.

20 25 From the foregoing description it will appear that there is no direct connection provided between the elements mounted on the castings 101 and the elements carried by the tabulator frame. Therefore, the punching attachment 30 may be readily removed from the tabulator without requiring any disassembly of screws or other connecting elements.

If gang punching of certain designating numbers or other card holes is desired, the requisite 35 setting pins 190 may be depressed by hand and locked in depressed condition by the means ordinarily employed for this purpose in the Powers key punch.

While we have described a preferred embodi-

ment of our invention, it is to be understood that the latter is capable of numerous modifications without departing from the spirit of the invention.

What we claim is:

1. In a combined punch and tabulator, in combination, storing means mounted on the tabulator settable in accordance with the position of the recording elements of the tabulator, means to set the said storing means after each total 10 recording cycle of the tabulator, means to retain said storing means in position between successive total recording cycles, punching means separately mounted but arranged to abut said tabulator, said punching means having punch 15 selecting members settable in accordance with the setting of said storing means to read the setting of said means and to control punches to punch a card in accordance with the reading during the interval between successive total re- 20 cording cycles of the tabulator.

2. A punch and Powers type tabulator combination comprising stepped sectors mounted on the tabulator and adapted to be positioned in accordance with the position of the accumulator 25 actuators of the tabulator, a rocking frame operable when a total is taken to set the sectors, means to retain the set sectors in position between successive total takings, and punching means separately mounted but arranged to abut 30 said tabulator, said punching means including slides positionable in accordance with the setting of said sectors, punches selected by said slides and a driving mechanism controlled by the total taking operation and effective to cause the opera- 35 tion of selected punches.

WILLIAM KUHLMAN.
PAUL BECKER.

CERTIFICATE OF CORRECTION.

Patent No. 1,998,281.

April 16, 1935.

WILLIAM KUHLMAN, ET AL.

It is hereby certified that error appears in the printed specification of the above numbered patent requiring correction as follows: Page 3, first column, line 38, for "permit" read print; and that the said Letters Patent should be read with this correction therein that the same may conform to the record of the case in the Patent Office.

Signed and sealed this 25th day of June, A. D. 1935.

Bryan M. Battey
